UNITED STATES PATENT OFFICE.

THOMAS TERRELL, JR., OF LONDON, ENGLAND.

VAPOR LAMP OR STOVE OF THE PRESSURE TYPE.

Application filed September 20, 1927, Serial No. 220,699, and in Great Britain September 21, 1926.

This invention relates to vapor lamps or stoves of the pressure type and has for its object to provide an improved form of generating or vaporizing device applicable thereto.

Hitherto these devices have possessed the defect that the heat necessary to vaporize the paraffin or the like ascending to the burner causes a certain proportion of the paraffin or the like to be cracked with the result that an amount of free carbon is formed which in time clogs the vaporizing tube and the burner orifice or orifices to such an extent that the lamp or stove ceases to function.

15 The object of the present invention is to overcome the difficulties hitherto experienced by providing improved means for feeding the vaporized paraffin or the like to the burner and for trapping or collecting free carbon 20 and thus preventing it from reaching and clogging the burner orifice.

According to the invention an improved method of vaporizing paraffin or the like is provided which consists in heating the liquid fuel ascending through a vertical tube and in causing expansion and cooling of the vaporized fuel in such a manner that its direction of flow is changed and its free carbon content is removed. The vapor ascending 30 from a heated feed tube is preferably caused to change its flow from an upward to a downward direction and again to an upward direction in passing through a succession of devices constituting traps for free carbon before reaching the burner orifice. According to one form of the invention, the ascending vapor is deflected so as to cause it to pass in succession through two receptacles in which free carbon can collect. According to the 40 preferred form of the invention the feed tube through which the paraffin or the like ascends from the reservoir of the lamp to the burner is open at its upper end but is provided with a partition a short distance below the upper 45 end which prevents the paraffin from taking a direct upward path to the burner. The interior of this tube is provided with a roll or filling of metal gauze which is preferably secured in position in such a manner as to 50 be readily renewable without any possibility of freed carbon entering the burner nipple during the operation of removing the gauze. At a point a little below the partition in the tube a number of perforations or slots may 55 be made in the wall of the tube which communicate with a chamber entirely surround-

ing the upper portion of the tube such chamber being preferably domed or coned at its upper end where it is provided with a screw threaded seating for a detachable burner 60 nozzle the lower end of which enters but does not engage the upper end of the aforesaid supply tube.

Reference will now be made to the accompanying drawings which illustrate by way of example constructions according to the invention and in which:

Figure 1 is a section through the feed tube, burner and associated parts of a pressure vapor lamp and

70 Figure 2 is a sectional elevation of the corresponding parts of a lamp suitable for burning petrol.

In the form shown in Figure 1 the feed tube 1 through which the paraffin is caused to ascend to the burner by the pressure of air pumped into the paraffin reservoir in the well known way, and which is arranged to be heated by the flames in the mantles 2, so as to provide a continuous supply of vaporized 80 paraffin, contains a roll of metal gauze 3 which extends to a point near the top of the tube.

At a point between the upper limit of the metal gauze 3 and the upper end of the tube 85 1 the tube is blocked by means of a partition 4, and the tube is formed at points above and below this partition with openings 5 through which the tube communicates with an annular expansion chamber 6 which surrounds the 90 tube 1 adjacent the partition 4. The bulb 6 or expansion chamber is preferably made in two parts which are screw threaded into the central feed tube 1 and all joints between these parts are silver soldered or brazed to 95 prevent leakage of paraffin to the exterior of the tube or bulb. The bulb 6 is also placed as high as possible above the flames so as to localize cracking of the paraffin vapor.

100 At its upper end the tube 1 carries a fine nozzle 7 constituting the burner orifice which is screwed into the upper end of the tube so that it can be removed for cleaning purposes and which is provided with a tubular extension 8 screwed into the body of the nozzle 7 and provided internally with three convex pieces of metal gauze 11. This tube 8 projects into the tube 1 to a point below the 105 openings 5 above the partition 4 so that the vaporized paraffin is caused to flow downwardly between the tubes 1 and 8 and then

upwardly through the tube 8 to the nozzle opening as indicated by the arrows.

The nozzle 7 projects into a mixing chamber 9 formed with an opening 10 through 5 which air is drawn into the mixing chamber around the nozzle 7 and a pair of mantles 2 are carried on tubes or ducts 12 connected to the mixing chamber 9.

In the operation of the arrangement shown 10 in Figure 1 the ascending paraffin becomes heated as it nears the upper end of the supply tube by the heat of the flame in the mantles 2, and as certain proportion of the carbon formed is caught by the meshes of the gauze lining in the tube 1. The vaporized product 15 passes outwardly through the perforations 5 below the partition 4 into the expansion chamber 6 which also acts as a trap for free carbon. The vapor is now free of much of 20 its carbon and descends through the annular space between the tubular extension 8 and the supply tube 1 wherein a further deposit of carbon takes place. The course of the vapor is now changed to an upward one, and 25 it ascends through the extension 8 which serves to deflect any remaining carbon away from the actual nozzle orifice by reason of the downward motion which it imparts to the vapor as it leaves the bulb 6 and also by 30 reason of the gauze elements 11. By this construction arrangements are provided for trapping free carbon in four separate ways, that is by means of the gauze lining, the chamber, the upper end of the supply tube, 35 and the interior of the burner. The co-operation between these devices in providing an illuminating vapor substantially free from carbon materially lengthens the life of the burner as not only is the fine burner orifice maintained practically free from carbon but 40 the device itself is so constructed that its various parts may be easily dismantled for cleaning purposes.

In the form of construction shown in Figure 2 which is specially adapted for petrol 45 burning lamps an expansion chamber 13 is connected to a nozzle 14 and a supply tube 15 respectively by swan neck tubes 16 and 17. The interior of the expansion chamber 13 is 50 of a construction similar to the chamber 6 in Figure 1 and within the upper portion of the tube 16 is disposed a piece of metal gauze 18. To prevent surging of petrol in the tube 17 its interior is fitted with two pieces of coarse 55 metal gauze 19 and 20 between which is disposed a wad 21 of asbestos fibre. The base of this tube 17 is screw threaded for engagement with the reservoir of the lamp or with a tube extending upwardly therefrom. The 60 position of the mantles is indicated by the broken lines 22 and these are sufficiently close to the lower curved portion 23 of the tube 17 to enable a match applied to this portion of the tube to serve the dual purpose of heating 65 the tube which is of thin metal and of light-

ing the incandescent burners. The operation of the device in eliminating free carbon particles from the ascending petrol vapor is the same as that described with reference to Figure 1.

While the invention has been described and illustrated as applied to a vapor lamp it will be understood that the invention is also applicable to a vapor stove of the pressure type.

I claim:—

1. A generator or vaporizer for vapor lamps or stoves of the pressure type wherein the feed tube through which the vapor ascends from the reservoir of the lamp or stove 80 to the burner is provided with a filling of metal gauze and is blocked at a point near the burner orifice being provided above and below this point with openings communicating with the interior of a closed expansion chamber surrounding the tube, the vapor leaving said chamber by the upper openings and being deflected downwardly by a tube of smaller diameter extending into the upper end of the blocked feed tube and ascending through said 85 90 smaller tube to the burner orifice.

2. A generator or vaporizer for vapor lamps or stoves of the pressure type, including a feed tube, a burner orifice at the upper 95 end of said tube, an expansion chamber, and means for causing the vapor ascending in said tube to flow from said chamber inwardly and downwardly and then upwardly to said burner orifice.

3. A generator or vaporizer for vapor lamps or stoves of the pressure type, including a feed tube, a burner orifice at the upper 100 end of said tube, means for closing said tube near its upper end to form a receptacle for free carbon, said tube having apertures above and below said closing means, and an expansion chamber communicating with said tube through said apertures.

4. A generator or vaporizer for vapor lamps or stoves of the pressure type, including 110 a feed tube, a partition closing said tube near its upper end, said tube having apertures above and below said partition, an expansion chamber communicating with said tube through said apertures, and a burner orifice on 115 said tube having a tubular extension projecting into said feed tube to a point short of said partition.

5. A generator or vaporizer for vapor lamps or stoves of the pressure type, including 120 a feed tube, having a filling of metal gauze to constitute a trap for free carbon, a partition closing said tube near its upper end, said tube having apertures above and below said partition, an expansion chamber communicating with a tube through said apertures, and a burner orifice at the upper end of said tube.

6. A generator or vaporizer for vapor lamps or stoves of the pressure type, having 125 incandescent burners, including a feed tube, a 130

burner orifice at the upper end of said tube, means for closing said tube at its upper end, said tube having apertures above and below said closing means, and an expansion chamber 5 communicating with said tube through said apertures, said tube being curved downwardly between the incandescent burners and upwards to the expansion chamber for the purpose of providing a portion adapted to be 10 heated in starting the operation of the lamp.

7. A generator or vaporizer for vapor lamps or stoves of the pressure type, including a feed tube, a burner orifice at the upper

end of said tube, means for closing said tube near its upper end, said tube having apertures 15 above and below said closing means, and an expansion chamber communicating with said tube through said apertures, said feed tube being provided near its lower end with two fillings of metal gauze, with a wad of asbestos 20 fiber between them for the purpose of preventing surging of petrol or the like from the reservoir into the feed tube.

In witness whereof I affix my signature.

THOMAS TERRELL, JR.
